(57) CLAIM

The ornamental design for a wiper rubber, as shown and described.

DESCRIPTION

FIG. 1 is a perspective view of a wiper rubber showing my new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof;

FIG. 8 is a cross-sectional view thereof along the line 8—8 shown in FIG. 1;

FIG. 9 is a perspective view thereof; and,

FIG. 10 is a perspective view thereof;

FIG. 11 is a perspective view thereof; and,

FIG. 12 is a perspective view thereof.

The break in the drawing figures show indeterminate length. In the drawings, the broken lines in FIG. 12 depict a wiper connector and form no part of the claimed design.
